ART OF DREDGING.

No. 318,860.

Patented May 26, 1885.

UNITED STATES PATENT OFFICE.

ALPHONZO B. BOWERS, OF SAN FRANCISCO, CALIFORNIA.

ART OF DREDGING.

SPECIFICATION forming part of Letters Patent No. 318,860, dated May 26, 1885.

Application filed April 21, 1885. (No model.)

To all whom it may concern:

Be it known that I, ALPHONZO B. BOWERS, civil engineer, residing at San Francisco, in the county of San Francisco and State of California, have invented certain new and useful Improvements in the Art of Dredging, of which the following is a specification, this application being a division of my application filed December 9, 1876, renewed April 16, 1879.

This invention relates to dredging; and it consists in certain improvements in the art of dredging by which the dredge-boat may be conveniently moved into operative position, and worked to advantage in such position, my said art of dredging also including methods by which the excavated material is raised and conveyed to a distance; also, in methods by which the excavated material may be forced to a very considerable distance and the conduit prevented from choking, these steps, constituting my improvement, being hereinafter pointed out in the claims.

I do not herein claim the apparatus described, and illustrated in the accompanying drawings, nor the method of raising submerged pipes, the same being claimed in other divisions of my original application, hereinbefore referred to; but this apparatus can be conveniently used to carry my improvements, herein set forth, into operation.

In the drawings, Figure 1 is a plan of a portion of my dredging apparatus. Fig. 2 is a vertical "fore-and-aft" section of a portion of the hull through the well, in which rotates the turn-table with a side view of the turn-table, vertical anchors, and hoisting apparatus. Fig. 3 is a vertical cross-section of a portion of the hull through the counter-balance cylinder and longitudinal well, showing, also, an end view of the bucket-wheel and the arrangement of the counter-balance and hoisting apparatus. Fig. 4 is a view of the inner chamber or shield, around which the bucket-wheel usually revolves. Fig. 5 is a longitudinal section through the discal ends of the bucket-wheel in the line *s s*, Fig. 8, showing, also, where the shaft *R* is secured to the hub of the cutting-wheel, and the outlines of two of the buckets *k k*, connecting the discal ends *b b*. Between these buckets is shown a longitudinal section of the inner chamber, *T*, and shaft *R* and bearing of this shaft *R'*. Fig. 6 is a side view of the bucket-wheel excavator. Fig. 7 is a cross-section of the bucket-wheel,

inner chamber, and driving-shaft through the line *t t*, Fig. 6. Fig. 8 is a view of the outer discal end of the bucket-wheel, showing a detachable ring-knife, *d*, and cutting-lips *e*. Fig. 9 is a reduced side view of the dredge-boat *A*, vertical anchors *G G'*, flexible connection *D*, floating and oscillating discharge-pipe *C'*, supported by hollow floats *P*, flexible connection *D'*, between the oscillating and non-oscillating sections of the discharge-pipe, mud-receiver *X*, (the details of which are shown in Figs. 13 and 14,) suspended discharge-pipe *3*, with its buoys *4 4*, submerged discharge-pipe *5*, resting upon the bottom, (over which a vessel is represented as passing,) and guys *6 6* for holding the discharge-pipe in proper position. Fig. 10 is a plan of the dredging and transporting apparatus, showing, also, a representation of a vessel passing over the discharge-pipe, and of the cut made by the dredger as it swings from side-to side. Fig. 11 is an enlarged cross-section of the discharge-pipe *C'* and hollow floats *P*. Fig. 12 is a view of the under part of a section of the discharge-pipe, showing numerous openings therein for the escape of the heavier and coarser material, while the water and lighter material are propelled onward to a further point of discharge. I do not confine myself to any peculiar form or arrangement of openings, one or more of which may be placed anywhere along said conduit where it may be desirable to discharge a portion of the spoil. Fig. 13 is an enlarged side and part sectional view of the mud-receiver, with its pipes, valves, and relay-pump, showing how the charging and discharging of a large receiver may be facilitated by the duplication of the branches and valves *Y Z*. Fig. 14 is an enlarged cross-section of the mud-receiver *X*.

In all these figures like letters indicate like parts.

A is a floating vessel, that carries the engines, boilers, and dredging machinery. It is shown in this instance with an elongated longitudinal well for the reception of the swinging portion of the suction-pipe.

B is a large pump, that draws the spoils from the buckets of the excavator up the suction-pipe and forces them through the discharge-pipe to a place of deposit.

B', Fig. 13, is a relay-pump or other auxiliary discharging apparatus, sometimes used in connection with a primary transporting appa-

ratus to carry the spoils to a greater distance than could conveniently be done by the original agent, power, or pump, or than would be practicable without subjecting the apparatus 5 to a pressure that might endanger some of the parts, or without the use of heavier or more expensive apparatus than would be desirable for ordinary purposes. It may also be used for discharging the receiver X, and for example, 10 hausting water from pipe C', (when said pipe is submerged,) for the purpose of raising it preparatory to floating it into a new position. As many of these pumps may be used as are necessary to transport the spoil to the required 15 distance.

C is a suction-pipe connecting the excavator with the pump B. The swinging portion of this pipe is mounted at the inner end of the well upon strong trunnions, one of which 20 forms an elbow of the pipe, and passes through a stuffing-box or other suitable connection into the suction-pipe of the pump B. Through the other trunnion passes a shaft that actuates the gears i, that drive the shaft R and bucket-wheel E, and upon these trunnions the shaft R, suction-pipe, and excavator swing as the cutter is raised or lowered to suit the depth at 25 which the work is progressing.

C' is a discharge-pipe. It is provided with 30 a strong flexible section, D, or other suitable joint or mounting at or near the turn-table F or other pivot or center of oscillation of the dredging-machine or excavating apparatus, and is constructed and arranged to permit 35 said apparatus or machine to swing horizontally upon said pivot or pivots without materially changing the position of said discharge-pipe beyond said mounting, flexible connection, pivot, or pivots. When this pipe is several 40 hundred feet in length, I usually support the inner portion by long narrow hollow floats, in which case it consists of two parts—an inner oscillating or swinging section (generally composed of several short sections flexibly 45 joined to each other and to the dredge-boat) and an outer stationary or non-oscillating section flexibly joined to said inner section. This permits the boat to feed forward, and the oscillating section to swing (with the advancing boat) on the joint connecting the oscillating and 50 non-oscillating sections. The discharge-pipe is provided with the pressure-gage 7, to give notice of overpressure and danger of choking of pipe from any sudden change in character 55 of spoil. When pipe C' is above deck and extends but a short distance from the mounting D for discharging alongside, it requires supporting, and is usually suspended from a mast, the claim for which is reserved for another application, now on file.

C" is a pipe passing through the receiver X to the exhausting apparatus of said receiver. When used in connection with the pipe C', it may be regarded as the prolongation of said 60 pipe.

C' is an auxiliary discharge-pipe used in connection with any suitable auxiliary trans-

porting apparatus, and extends from said auxiliary to another auxiliary transporting agent or apparatus, or to a place of deposit.

C', Fig. 10, is a discharge-pipe extending from a second relay discharge apparatus to a place of deposit. When a floating discharge-pipe would impede navigation, the greater portion may lie upon the bottom 5, Fig. 9, and when the water is too deep for this it may be suspended from the buoys 4, Fig. 9, and guys and anchors 6 may, if necessary, be used to prevent the discharge-pipe from being disturbed by winds, waves, or currents. When the pipe is to be submerged, it may be advisable to construct it of thin metallic plates, uniting the several sections with ball-and-socket or other strong flexible connections. In other cases it may be made of wood or metal, according to the preferences of the user.

E is a rotary bucket-wheel excavator, having radiating bottomless buckets k, Figs. 1, 5, 6, 7, firmly secured at each end to the discal ends b b of said excavator. These buckets 90 may be stiffened, strengthened, and protected by rings or screens d, passing around, secured to, and preferably projecting beyond the edges of said buckets, Figs. 1, 5, 6, 7, 8. These rings may be sharp to cut like the revolving 95 disk colters of plows, and serve to divide the material entering the buckets and to exclude substances too hard to be cut and too coarse to pass through the pipe and pump. They serve also as fenders, to enable the cutter to ride over obstructions without catching and breaking. The edges of the buckets are sharp and may be provided with detachable steel knives or cutters S, Fig. 6, for working 100 in hard material.

The outer discal end, Figs. 1, 3, 6, 8, may be provided with cutting-edges, lips, or scoop e, to obviate the danger of breakage from jamming against a hard bank as the dredger heaves in the swell of the sea. In making the necessary openings in the discal end to admit the silt from said scoops said end plate becomes changed to the form of a spider or series of arms, which may be strengthened by the lower ring, d, which may in turn be regarded 115 as forming a series of braces extending between the said arms at or near their outer parts. The several parts of this excavator may be made separate and detachable, or it may be cast in a single piece. I do not confine myself to the precise mode described of mounting this excavator-wheel or of freeing it 120 of its contents. It may be of any desired size and proportion of parts, and may discharge its contents inward through itself into any suitable conduit or receiver. The rings d may be omitted in soft mud free from substances too coarse to pass through the pipe and pump, though always at the risk of the projecting buckets catching upon obstructions and getting broken.

F, Figs. 1, 2, 10, is a small cylindrical turn-table rotating in a circular well or frame. It is provided with a strong flange or other suit-

able bearing, and is rotated in any convenient manner. Two or more vertical apertures, *e e*, pass through the turn-table from top to bottom on opposite sides, as shown.

5 G G², Figs. 2, 9, are vertical anchors passing loosely through the apertures *e e* in the turn-table into the mud below. They are raised by blocks and tackle attached to the mast *f*, or in any other usual manner.

10 H is a counter-balance cylinder connected with the suction-pipe, excavator, and hoisting apparatus to obviate the danger of breakage from pounding upon the bottom in a heavy swell. It is provided with a piston, piston-rod, and gland like a steam-engine. Steam or compressed air is admitted to the upper side of the piston, the area of which is sufficient very nearly to balance under the given pressure the weight of the suction-pipe and excavator. To the upper end of the piston is attached the hawser *L*, passing over suitable sheaves in the frame *K*, thence through the block *g*, Fig. 3, whence it passes over other sheaves in said frame to the windlass *J*, by 15 which means the excavator can be raised or lowered by said windlass without interrupting the action of the counter-balance. When the dredger rises on a swell, the excavator rises also, and as the dredger sinks in the trough of 20 the sea the excavator falls upon the bottom, not with the full weight of the excavator and suction-pipe, but with the unbalanced weight only, striking so lightly as not to endanger the safety of the wheel. This device is necessary 25 only when dredging a hard bottom in a heavy swell. When not required for this purpose, the cylinder *H* may be utilized as a steam or hydraulic hoist, or be dispensed with altogether.

30 I is a variable winding device, of which there are many suitable forms. I prefer ordinary winding-drums driven by a separate engine, though for simplicity of illustration I have shown tapering drums *h h*, loosely mounted on a shaft and driven (through V-shaped friction-couplings and suitable connections) by the 35 main engine. The disengaged drum gives out one warping line as the engaged drum takes in the other. The office of this device is to vary the speed of the side feed for the purpose 40 of regulating the percentages of earth and water delivered to the pump, (without affecting the speed of other parts of the machine.) This speed (with the device shown) is dependent upon the diameter upon which the warping 45 lines wind, and is varied by shifting the sliding guide-sheaves *i i* toward or from the larger ends of the drums by means of the hand wheels and screws, as shown.

50 J is a windlass for raising and lowering the excavator.

K is a frame from which the suction-pipe and excavator are suspended.

L is a line or chain for raising, lowering, and counterbalancing the excavator.

55 M M are warping lines passing from the hold to the winding-drums *h h*, around which they make a sufficient number of turns to pre-

70 vents slipping, whence they pass around suitable guide-sheaves to and through the anchored blocks *U U* to the outer end of the suction-pipe to which they are secured, so that the working side strain falls mostly upon the outer end of the suction-pipe, (or of the ladder supporting said suction-pipe, if such be used,) and but lightly upon the joints or trunnions supporting the inner ends of said pipe or ladder. As the outer ends of these lines wind upon the drums in the device shown, the inner ends unwind and descend to the hold. The office of these lines is to swing the excavating apparatus or the dredger from side to side in the process of dredging, and firmly to anchor the excavator end of the dredger when it is not at work, which latter is accomplished by simply engaging both drums *h h* in their friction-couplings.

75 N is a force and suction pump. It is used to exhaust the water from the discharge-pipe for the purpose of raising the submerged portion to dilute the spoils, so that they will spread over a large area of land, or to enable them to be transported through long pipes without the aid of a relay-pump to clear the pipes when accidentally choked, should this ever occur, and to prime the pump *B*, the latter or its 80 suction-pipe being provided with the usual valve or valves for this purpose. Like most steam-pumps, it is provided with two suction-orifices on opposite sides of the water-chamber and a discharge directly over each suction. 85 To the suction and discharge on one side is connected the branch pipe *O*, leading into the pipe *C'*. Each branch is provided with valves in the usual manner of arranging a branch pipe to serve for suction and discharge. The 90 discharge branch only is shown, the suction being directly under it. To the suction on the other side of the water-chamber is secured a valve and pipe communicating with any suitable supply of water (usually that in which the dredger floats) and sometimes by a branch pipe and valve with the hold of the vessel for discharging leakage, and by another branch and valve with pump *B* for priming said pump by suction. To the discharge above 95 this suction is connected a pipe or hose, that may also be used for priming the pump *B* by discharging into it, and for all the various purposes of an ordinary ship-pump. When 100 *O* is used as a suction-pipe to draw from pipe *C'*, the valve on the discharge branch is closed, the suction branch valve is opened, and the discharge is through the pipe or hose on the opposite side. When *O* is used as a discharge-pipe to force into pipe *C'*, the suction branch 105 valve is closed, the discharge branch valve is opened, and the suction is through the opposite suction-pipe. When the suction is through the pipe opposite the suction branch of pipe *O*, the discharge may be through the pipe or 110 hose above it or through the discharge branch of *O* into pipe *C'*, as regulated by the valves, to suit the purposes of the user.

115 O is a pipe with branches and valves con-

necting both suction and discharge on one side of the pump N with pipe C', and is either a suction or discharge pipe, as regulated by its valves.

5 P P are long narrow hollow floats, preferably extending longitudinally along each side of the short sections of the discharge-pipe for supporting them on the water. They may be made of wood or metal, and be secured together and to the discharge-pipe by pieces of scantling passing crosswise over and under the pipe and floats, and fastened with rods passing each side of the pipe and floats, as shown in Fig. 11, though I do not confine myself to this form of construction.

Q is a pulley or gear for actuating the gears i and excavator E. It may be connected with its shaft by a friction-coupling.

R is the driving-shaft of the bucket-wheel. It is keyed or otherwise secured to the hub of the wheel, whence it passes through suitable bearings in the inner chamber up the suction-pipe and through a stuffing-box to the gears i, by which it is actuated.

S is a strong detachable steel knife, sometimes used on the edges of the buckets when working in hard material. It may be serrated, chisel-toothed, or straight-edged, according to the character of the materials to be cut, a straight edge being preferable for ordinary work.

T is an inner chamber or shield, around which the bucket-wheel revolves and into which it discharges. This chamber is provided with a strong flange, by which it is secured to a similar flange on the end of the suction-pipe. It is also provided with a large opening, a, Figs. 4, 7, through which the spoils enter from the buckets, and through this opening, Fig. 4, is seen a portion of the driving-shaft R and the bearing of said shaft in the end of said chamber. This chamber or shield forms a bottom for the buckets h until they reach the opening a, as shown in the cross-section of the wheel and chamber, Fig. 7. As the buckets pass this opening, they discharge mud and water into the chamber, as indicated by the inner arrows, the outer arrow showing the direction of rotation. The office in part of this chamber or shield is to prevent too large a percentage of water from entering with the mud; but when the spoils are of a character to require a large percentage of water to carry them up the suction-pipe or to send them through the discharge-pipe, as may sometimes be the case, the chamber may be cut away until only enough remains to support the excavator and shaft R.

U U are blocks anchored at suitable points on each side of the dredger through which pass the warping lines M M, for the purpose of swinging the dredger or the excavating apparatus from side to side. They are usually placed from three hundred to six hundred feet apart and a little in advance of the ends of the first cuts made by the excavator to allow a wide swing and avoid the necessity for

too frequent change of place as the work progresses.

V is a branch pipe and valve, through which samples of the spoils are drawn from the discharge-pipe to enable the operator properly to regulate the speed of the side feed. It is preferably placed about one-third the diameter of the discharge-pipe from the lower side 75 of said pipe, in order to secure a fair average sample.

W is a small tank resting upon scales. It is provided with a discharge pipe and valve. It is filled with spoils drawn from the discharge-pipe through the branch and valve V, and the speed of the side feed is increased or diminished according to the weight of the spoils.

X is a floating mud-receiver carrying the relay-pump or other auxiliary discharging apparatus, B', and its actuating machinery. The main purpose of this receiver is to permit the excavator to run continuously, although the relay-pump be stopped for a little while, the receiver affording a receptacle for the spoils in the meantime. Longitudinally through this receiver passes the pipe C'' to the auxiliary discharging apparatus B', whence the pipe C'' extends to another auxiliary discharging apparatus or to a place of deposit.

Y is a valve on the pipe C'' within the receiver X. This valve is adjusted to open automatically outward with slight pressure, and serves as a relief-valve in case of stoppage of the pump B' while the pump B is running. It serves also as a guide to regulate the speed of pump B', which should be increased beyond that necessary for preventing the opening of this valve, in order to aid by suction as well as forcing. This valve may be set wide open for the purpose of filling the receiver, and may be securely closed when the pump B is used to force the material into the pump B', for the purpose of increasing the efficiency of the latter. It is also opened to admit air into the discharge-pipe when the water is to be withdrawn therefrom by pump N.

Z is a branch and valve through which mud is drawn from the receiver to be discharged through the pipe C'.

Z' is a branch and valve for admitting water to wash out the pipe C' after the mud has been discharged from the receiver.

Z'' is a valve for closing the pipe C'' while the mud-receiver is being discharged, or when said receiver is disconnected from the pipe C', and takes the mud directly from the dumping or dredging apparatus.

Z''' is a pipe and valve used for admitting water through the bottom of the receiver for the purpose of diluting the mud when it is too stiff to pass freely up the branch Z. It may have branch-pipes, with numerous small openings, for the more thorough dilution of the spoils. This receiver may be used in connection with any dredging apparatus for continuous transportation of the spoils through pipes as the work progresses; or it may be filled,

towed to the place of deposit, and there be connected with a discharge-pipe for putting the spoils on shore.

The operation of dredging is as follows: The 5 vertical anchors and excavator being raised to allow freedom of motion, the dredger is placed in position with the turn-table in line with the longitudinal axis of the proposed cut. The turn-table is then rotated until the vertical 10 anchors are also in line with said axis, and both anchors are then dropped into the mud. The discharge-pipe is placed in position, the blocks U U anchored at suitable points for swinging the machine, and the dredger swung 15 round until the excavator reaches the side of the proposed cut, as shown in Fig. 10. The lines M M are drawn faut, and the excavator lowered below the surface of the water. The pump B is then primed, started, and the excavator 20 set in motion and lowered its entire diameter into the mud. The proper winding-drum is then engaged, and the dredger, swinging on the turn-table as a pivot or center of oscillation, rapidly cuts its way to the opposite 25 side. To secure a steady side feed, the friction-coupling of the unwinding-drum may be adjusted to keep the unwinding-line sufficiently taut to prevent veering of the dredger with wind or tide. Upon reaching the opposite side, 30 the winding-drum is disengaged, the excavator again lowered its full diameter, the side feed reversed, and the dredger cuts back again. This process is repeated until the proper depth is obtained. The excavator is then 35 raised above the bank in front, the anchor G raised, as shown in Fig. 2, and the turn-table rotated upon the anchor G² until G is squarely in front of G² in line with the longitudinal axis of the proposed excavation, as indicated 40 by the broken-lined outline G', Fig. 2. G is then dropped into the mud, and the work proceeds as before, the dredger having been fed forward the distance between the centers of the vertical anchors, which is fixed to correspond 45 with the cut capable of being made by the excavator. This arrangement for feeding forward keeps the center of oscillation of the dredger coincident with that from which the arc to be cut by the excavator should be 50 described.

A less perfect forward feed is secured by placing the dredger so that the excavator is at the side and the turn-table in line with the longitudinal axis of the proposed excavation. The turn-table is then rotated until the vertical anchors are in a line parallel with the transverse axis of the dredger, where it is made stationary. This leaves one anchor 55 diagonally in advance of the other, the dredger lying diagonally across one half of the line of the proposed excavation. The forward anchor is now dropped into the mud to form a pivot upon which the dredger swings as it cuts to the opposite side. The dredger then 60 lies diagonally across the other half of the line of the proposed excavation, the swing having brought the rear anchor to the front.

This anchor in its turn is dropped to form a new pivot, and the other anchor is then raised. The dredger swings first upon one 70 and then upon the other anchor, these anchors being alternately raised and lowered for this purpose. As this mode of feeding by swinging alternately upon two different pivots gives a wedge-shaped cut requiring two 75 full swings to make one full cut, it is equivalent to a loss of one-half of the time, and is used only to prevent stoppage of work when the apparatus for rotating the turn-table is stopped for repairs or other cause, in which 80 case it becomes valuable.

What I claim in this division of my application is—

1. The improvement in the art of dredging, which consists in oscillating the dredge-boat 85 on a center, thereby continuously removing the spoil from an arc-shaped surface, conveying the same into the boat, and forcing it thence through a closed conduit by a series of impulses, diluting the spoils in its passage to facilitate discharge.

2. The improvement in the art of dredging, which consists in successively oscillating a dredge-boat about a contained center, thereby removing successive arc-shaped layers 95 while swinging sidewise, substantially as described.

3. The improvement in the art of dredging, which consists in oscillating the boat on a contained center, thereby making an arc-shaped cut during the side movement of the boat, substantially as described.

4. The described method of dredging, which consists in oscillating the dredge-boat on a contained center, and by such oscillation forcing the excavator continuously sidewise, and so making an arc-shaped cut and continuously bringing the excavated material inward, substantially as described.

5. The described method of dredging, which 110 consists in oscillating the dredge-boat on a center, and by such oscillation forcing an excavator continuously sidewise, thus making an arc-shaped cut and drawing the excavated material inboard by suction.

6. The method of diluting the spoils to facilitate its discharge, which consists in forcing the same through a closed conveyer, and forcing a supplementary diluting substance into said closed conveyer.

7. The method of conveying mud from a dredger, which consists in forcing it continuously through a closed conduit by a succession of forward impulses, as set forth.

8. The process of transporting mud and 125 semi-liquid material, consisting in forcing the same through a succession of coacting pumps and pipes to a place of deposit.

In testimony whereof I affix my signature in presence of two witnesses.

ALPHONZO B. BOWERS.
